UNITED STATES PATENT OFFICE.

LUTHER B. THOMAS, OF RINGGOLD, LOUISIANA.

WELL-BUCKET.

No. 888,551.

Specification of Letters Patent.

Patented May 26, 1908.

Application filed January 31, 1907. Serial No. 355,094.

To all whom it may concern:

Be it known that I, LUTHER B. THOMAS, a citizen of the United States, residing at Ringgold, in the parish of Bienville and State of Louisiana, have invented a new and useful Well-Bucket, of which the following is a specification.

This invention relates to well buckets, and its object is to provide a bucket of novel construction having means whereby the bucket will quickly sink when lowered into the water.

Heretofore in the construction of round buckets having valves in the bottoms thereof it has been necessary to so shape the valves as to prevent them, when open, from admitting a sufficient quantity of water to cause the bucket to promptly sink.

The present invention is designed to overcome this defect and consists of certain novel features of construction and combination of parts which will be hereinafter more fully described and pointed out in the claims.

In the accompanying drawing is shown the preferred form of the invention.

In said drawings,—Figure 1 is a vertical section through a bucket constructed in accordance with the present invention, the valve of the bucket being shown in dotted lines in raised position. Fig. 2 is a top plan view of the bucket. Fig. 3 is a bottom view thereof, and Fig. 4 is a detail view of the valve, detached.

Referring to the figures by characters of reference, 1 is a tubular bucket, the upper open end of which is circular whereas the lower end has a straight edge 2 formed by flattening the wall of the bucket along one side, said flattened portion gradually increasing transversely towards the bottom, as shown particularly in Fig. 2.

A ring 3 is secured around the bottom of the bucket and has an inwardly-extending flange 4 which is merely of sufficient width to constitute a seat or rest for the valve of the bucket. This valve consists of a body 5 of leather or other suitable material conforming somewhat to the contour of the bottom of the bucket and having a straight edge 6 which is secured by means of rivets 7 or in any other preferred manner, to the corresponding portion of the flange 4. Secured upon this body is a reinforcing plate 8 having an upstanding tongue 9 extending therefrom at the free end of the valve, and this tongue is adapted to limit the upward or inward movement of the valve by coming into contact with the flat wall of the bucket. Another plate 8^a is se-

cured upon the lower base of the valve body, the two plates 8 and 8^a being fastened by rivets.

A bail-like projection 10 is secured to the plate 8^a and is adapted to project beyond the lower end of the bucket so that when the bucket is placed on a board or other structure this projection will push the valve into the bucket so as to open the same and allow its contents to flow outward. It will be noted by referring to Figs. 2 and 3 that the valve is of slightly less width than the bottom of the bucket so that said valve is free to swing upward until its tongue 9 contacts with the flat face of the bucket. As practically the entire bottom of the bucket is then open it will be understood that the bucket will be free to instantly sink below the surface of the water in which it is placed.

The plate 8 extends over all portions of the body 5 of the valve, except that part thereof adjacent the securing means 7, and therefore the valve is prevented from buckling under the weight of the liquid contents of the bucket. By providing the tongue 9 the valve is prevented from swinging too far inward and, therefore, there is no danger of the same becoming locked and thereby prevented from promptly returning to its seat when subjected to downward pressure.

What is claimed is:—

A well bucket having a flattened wall at its inlet end, a flange surrounding the inlet, and a valve normally closing said inlet end and comprising a flexible member secured at one edge against the flat wall of the bucket and having its peripheral portion normally resting upon the flange, a reinforcing plate upon the lower face of said member and disposed to be surrounded by and to fit close to the flange, a bail-like projecting device upon said plate and normally extending below the bucket, a reinforcing plate upon the inner face of the flexible member, an integral folded tongue extending from the edge of and at right angles to said plate and constituting a stop, and means extending through the plates and flexible member for binding said plates upon the member.

In testimony that I claim the foregoing as my own, I have hereto affixed my signature in the presence of two witnesses.

LUTHER B. THOMAS.
